UNITED STATES PATENT OFFICE.

DANIEL T. CHAMBERS, OF WASHINGTON, DISTRICT OF COLUMBIA.

GLOVE-FASTENER.

SPECIFICATION forming part of Letters Patent No. 281,969, dated July 24, 1883.

Application filed March 9, 1883. (No model.)

To all whom it may concern:

Be it known that I, DANIEL T. CHAMBERS, of Washington city, District of Columbia, have invented a new and useful Improvement 5 in Glove-Fasteners; and I do hereby declare that the following is a full, clear, and exact description of the same, reference being had to the accompanying drawings, forming part of this specification, in which—

10 Figure 1 is a view of the back of a glove provided with my improved fastener. Fig. 2 is a cross-section through the line *x x*, and Fig. 3 is a view of the back of the glove with the wrist turned up and opened.

15 My invention relates to an improvement upon the glove-fastener for which Letters Patent were granted me February 27, 1883. In that case a peculiar arrangement of parts was made to form a fastening, in which the opening and the flap-piece came in the palm of the hand. For many uses it is desirable to have a glove with a smooth unbroken palm; and my present invention consists in such adaptation of my previous improvement to a glove 20 as will permit the slit and fastening devices to come at the bottom side of the glove, leaving the palm entirely smooth and unbroken.

25 In the drawings, A represents the glove, which, at its lower side, in line with the little finger, and next to the wrist, has an opening or slit, *a a b*. (See Fig. 3.)

30 To one side, *a a*, of the slit is fastened one end of a strap, B, which passes through a buckle-loop, C, attached to the inside of the glove on the opposite side of the slit, and thence runs to and is secured to a flap-piece, 35 D, fastened to the opposite side of the slit in line with the wrist-band.

40 In the end of the flap-piece D there is an eyelet or perforated grommet, *a'*, which performs the double function of fastening the strap B to the flap D and also forming an eyelet for fastening over the button *b'* when the glove is to be tightened upon the hand.

45 At the point where the strap B is fastened to the side *a a* of the slit there is a fly-piece, *c*, for lapping under the slit when closed; but this is not essential, and I may dispense with it.

50 Instead of making the flap D of the full width of the wrist-band, it may be a simple strap secured to the wrist-band, and only equal in

width to the width of the strap B, to which it is to be fastened; or I may dispense entirely with the flap D and place the buckle-loop near the edge *a b* of the slit, and provide a stop on the 55 strap, which, when the latter is drawn up tight, strikes against the buckle-loop and holds the edge *a b* from pulling open. I furthermore may make the flap D in one and the same piece with the wrist-band of the glove, 60 if found desirable to do so.

In the place of the metallic buckle-loop C, I may employ as its equivalent a loop or keeper, of buckskin, leather, or analogous material.

Having thus described my invention, what I 65 claim as new is—

1. A glove having a slit, *a a b*, at the lower side or in line with the little finger, in combination with a strap, B, secured to flap *c* or one side of the slit, a loop or keeper, C, fastened to the opposite inside edge of the slit, and through which said strap is passed, and a flap, D, fastened to the end of the strap B and adapted to be secured to a fastening, *b'*, on the glove, substantially as set forth. 70

2. The combination of the glove having slit *a a b* in line with the little finger with flap *c*, the loop or keeper C, strap B, and flap D, provided with a securing-eyelet, substantially as shown and described. 75

3. The combination, with the glove having button or fastening *b'*, of the strap B and the flap D, combined with and secured together by an eyelet or perforated grommet, *a'*, which also co-operates with the button *b'* to secure 80 the flap, as described.

4. The combination, with a glove having slit *a a b* in line with the outer edge of the little finger, of a strap, B, fastened at one end to the flap *c* or one side of the slit, and passing 85 through a loop or keeper on the other side of the slit, and having an eyelet or fastening at its end, substantially as and for the purpose described.

The above specification of my invention 90 signed by me in the presence of two subscribing witnesses.

DANIEL T. CHAMBERS.
